United States Patent Office.

E. M. MIX, OF WESTFIELD, NEW YORK.

Design No. 2,701, dated July 9, 1867.

DESIGN FOR A RIM-LOCK.

The Schedule referred to in these Letters Patent and making part of the same.

TO ALL WHOM IT MAY CONCERN:

Be it known that I, E. M. Mix, of Westfield, in the county of Chautauqua, and State of New York, have originated and designed a new and improved Design for Rim-Locks; of which the following is a full and exact description, reference being had to the accompanying photographic representations, making part of this specification, in which—

Figure 1 is a perspective view, and

Figure 2 a front elevation of the case of a lock of my improved design.

Like letters refer to corresponding parts in both figures.

My improvement consists of forming the periphery or edge of the lock-case and nosing of a cyma-reversa, the members of which are divided by a small fillet between, and the corners of the case rounded to avoid the angles, and those of the nosing in a similar manner.

As shown in the views, *a b* are the concave and convex members of the moulding, and *c* the fillet which separates them. I also construct the seat for the rose or knob *d* raised or elevated above the surface of the case, and surround the same with an ogee moulding similar to that of the edge of the case.

The effect of these mouldings and their combination is to give the impression of boldness, with grace and elegance, without the harshness and rigor which belong to those of angular form and finish.

What I claim as my invention, and desire to secure by Letters Patent, is the design for rim-locks herein described and shown.

In witness whereof I have hereunto signed my name in the presence of two subscribing witnesses.

E. M. MIX.
